UNITED STATES PATENT OFFICE.

GEORGE J. ZISCH, OF NEWARK, NEW JERSEY.

INSTANTANEOUS ELECTRIC WATER HEATER.

Application filed January 27, 1927. Serial No. 163,874.

This invention relates to devices for heating water as issuing from a supply source by means of an electric coil disposed in the water passage.

It very frequently occurs that a moderate quantity of hot water is required in a house or office and without delay, such as would be necessarily encountered by the usual methods of heating; therefore the main object of the invention is in the provision of means whereby such supply may become instantly available.

A further feature is to provide a heater that can be attached and detached from a source of water supply in a moment's time and which is immediately capable of increasing the temperature of an attenuated stream to any desired degree up to the boiling point.

Another aim is to produce a heater that can be easily taken apart for cleansing and reassembled by a person of ordinary intelligence.

A still further object resides in the provision of a heater entirely automatic in action and under the ready control of an operator.

These several advantageous features, together with others, such as simplicity, portability and inexpensive construction, are accomplished by the novel and practical construction and combination of parts herein-after described and shown in the accompanying drawing, forming a material part of this disclosure, and in which:

Figure 1 is a longitudinal sectional view of a water heater made in accordance with the invention.

Figure 2 is a transverse sectional view looking on line 2-2 of Figure 1.

In the drawing the numeral 5 designates in general the front end of a conventional bib cock such as is in common use and attached to its outlet, by screw threads or frictional engagement is a goose neck or reversed curved tubular loop or bend 6.

A cylindrical casing 7 of dielectric material is formed to present an open top and closed bottom having a short axial hub bored to receive a hollow stem 8 non rotatable but adjustable lengthwise, the lower end of the stem being threaded to engage the opening in the bend 6 and also a check-nut 9 disposed against the casing hub.

A conical chamber 10 is formed in the casing and tight fitted therein is a hollow cone 11 reaching nearly to the solid bottom of the casing.

The cone 11 has a raised hub bored to receive the stem 8 and is held adjustably by a check-nut 12.

The upper end of the stem is concave to receive packing 13 held by a packing rut 14 through which passes a valve rod 15 threaded into the stem and controlling ports 16 through its walls leading to the casing chamber 10, the rod terminating in a needle valve 17, to close or open the passage through the stem 8.

A cover 18 is secured over the casing to its outstanding top flange 19 and the inner top portion of the casing is annularly recessed to receive a packing ring 20 clamped by a rim 21 projecting from the hollow cone 11 by the cover to provide a liquid tight joint.

The hollow cone 11 has formed in its periphery a coarse helix 22 in which is loosely disposed the several convolutions of a high resistance coil 23, one end of which is attached to a binding post 24 and the other end to a similar binding post 25, these binding posts having connections 26 and 27 with a snap switch 28 carried on the underside of the cover 18.

The valve rod 15 extends axially through the cover 18 and is provided with an operating handle 29 by which entrance of liquid to the chamber 10 is controlled, this chamber being in open communication with the lowermost helical groove 22, while the upper groove is open to a dispensing conduit 30 entering through the casing wall in which it is threaded.

Also fixed on the rod 15 within the space 31 of the hollow cone 11 is an adjustable collar 32 having a projection 33 adapted to throw the switch into an off and on position by corresponding movement of the handle 29.

In operation water having been turned on at the cock 5 or other supply source, the same will enter the opening in the stem 8 and press against the needle valve 17.

Upon turning the handle 29 the rod 15 is rotated and, due to its thread, rises sufficiently to admit water past the valve 17, out of the openings 16 into the chamber 10.

Thereupon the water circulates through the grooves 22 in direct contact with the coils and passes out of the spout 30 into a receiver held to collect the issuing stream.

The handle 29 upon being further turned to permit a considerable stream to pass through the heater, acts upon the switch 28, to which current is delivered from any convenient

source of electricity, heating the coil 23 and the water flowing through and past the entire length of the coil in a manner well understood.

- 5 Obviously upon turning the valve handle in an opposite direction, the greater volume of water will first be reduced, then the switch opened and finally the water passage entirely closed.
- 10 From the foregoing it will be seen that a simple device for this purpose has been disclosed in the preferred form of its embodiment, but it is not desired to restrict the details to the exact construction shown, it being 15 obvious that changes, not involving the exercise of invention, may be made without conflicting with the scope of the appended claims.

Having thus described my invention, what I claim as new and desire to secure by Letters

- 20 Patent, is:—

1. An electric water heater comprising a cylindrical body having means to connect with a water supply source, said body having a conical chamber and an opening leading 25 thereto, a cover on the open end of said body, a hollow tapered plug having a raised helix on its periphery fitting the chamber, a high resistance wire coil disposed in the grooves of said helix, a snap switch controlling current 30 to said coil, a valve controlling the passage of water through the helical grooves, said valve having a stem extending through said cover, a handle thereon, an outlet on said body in communication with the groove most

remote from the water inlet and means actuated by said valve handle to operate said switch.

2. An electric water heater comprising a body having a conical chamber and a solid bottom, a tapered inner shell having a helical groove fitting the chamber, a cover attached to said body to impinge on the shell, a resistance coil in the shell groove, a snap switch carried by said cover within the shell chamber, packings for said shell, an inlet to said chamber below said shell, an outlet conduit from the opposite end of the groove passing radially through the wall of said body, means for controlling the inlet, said means extending through the cover, and means combined with said control means for actuating said switch.

3. An electric water heater comprising inner and outer dielectric shells having a conical joint and a helical groove therebetween, a spindle axially rotatable in said shells and provided with a valve controlling the passage of liquid through the groove, a dielectric cover, a snap switch carried by said cover to extend into the inner shell, a resistance coil controlled by said switch, said coil being disposed in the mentioned groove, a conduit leading from the groove through the outer shell, and an arm fixed on said spindle within the inner shell to open said switch after the flow of water has been initiated and to close said switch prior to completing the valve closure.

GEORGE J. ZISCH.
